UNITED STATES PATENT OFFICE

2,267,934

ENVELOPE OPENER

Andrew M. Lockett, New Orleans, La.

Application January 15, 1940, Serial No. 313,962

3 Claims. (Cl. 30—294)

This invention relates to a new and useful improvement in an instrument for opening envelopes and cutting paper.

One object of my invention is to provide an envelope opener having a cutting element consisting of a safety-razor blade.

Another object of my invention lies in the special mounting of the razor blade so that it may be easily and promptly inserted in and removed from its holder while remaining positively locked in place while the opener is in use.

A further object of my invention consists in the use of a holder for the cutting element such that it may be readily insertible beneath the flap of an envelope and while the latter is held on a table the opener may be pushed through in one stroke.

Still another object of my invention is to provide a device for the purposes herein described which will be light in weight, reliable in operation and of low cost of production.

The above and other objects and advantages of my invention will appear from the detailed description appended hereto and more particularly set forth in the claims.

In the drawing,

Figure 1 is an enlarged front elevation of my improved device;

Figure 2 is a side elevation thereof;

Figure 3 is a partial elevation of the device with the cutting element displaced from its normal position; and

Figure 4 is a cross-section on line 4—4 of Figure 1.

My envelope opener comprises, broadly, three parts, i. e., the one-piece body 1, the receptacle 2 and the cutting blade 3. The body 1 has a straight portion 1' beginning with a sharp end 4 and extending to a point 5; then it is bent or offset in a short portion 6 and then terminates in a long handle 7 also offset from the above mentioned straight portion but to a lesser angle than the short portion 6. Intermediate its ends the straight portion 1' has a depressed or cut-in curved edge 8 for a purpose which will appear later.

The receptacle 2 comprises a generally rectangular plate having an indented, stamped or pressed portion 9 for the purpose of providing a retaining shoulder or ledge 10. The receptacle 2 is secured to the straight portion 1' of the body 1 by suitable means such as rivets 11 and it will be seen that one edge of the receptacle is cut away as at 12 along a curve similar to and cooperating with curve 8 of the body.

As shown in Figure 4, the container 2 and the body 1 provide a niche within which the cutting blade 3 is housed, the fit of the blade within its housing being snug and just sufficient to hold the blade in position but still not so tight as to prevent the easy removal and reinsertion of another blade.

It will be evident that either new or discarded safety-razor blades may be used in my envelope opener and paper cutter but it is preferable, though not necessary, that such blades be used as have one cutting edge and an opposite, non-cutting and thicker edge, so that it can better be retained between the container 2 and the body 1 of the envelope opener.

In use, the envelope to be opened is laid flat on a table, the point 4 of the opener is inserted beneath the flap and the opener blade 3 is pushed through, cutting the flap's folded edge at one stroke. It is important to note that while the opener is operated as described, the handle thereof is held through the clenched hand and, due to the offset of the said handle the knuckles are left ample room so that they will not come in contact with the table.

The material composing both the body and the container is, preferably, aluminum or any other metal. The metallic walls of the container 2 are, therefore, resilient and help to retain the blade in its operative position. It will be understood, however, that any other substance such as Bakelite or any other material may be chosen.

The handle 7, due to its relatively large size and substantial width, may also be used to carry the name of the maker as well as any suitable advertising legend or design.

It will be realized that the materials composing my device are of very low cost and that the labor to assemble the parts, grind and polish them, is equally nominal.

Having thus set forth my invention, I claim as new and desire to secure by Letters Patent:

1. An envelope opener comprising a blade-carrying portion, said portion having a concave edge, a container secured to said blade-carrying portion and having a concave edge corresponding to the concave edge on the blade-carrying portion, a flat removable blade insertible and held in and between said container and said blade-carrying portion in flat condition, said blade having its cutting edge protruding beyond said concave edges, said blade being removable by a straight pull away from the container, and a handle depending and angularly offset from said blade-carrying portion.

2. An envelope opener comprising a blade-carrying portion, a perforating portion at one end thereof, a handle portion at the other end thereof, said handle portion being angularly offset from said blade-carrying portion, a container secured to said blade-carrying portion, said blade-carrying portion and said container having cooperating and corresponding concave edges, and a flat removable blade insertible and held in and between said container and blade-carrying portion in flat condition and having a cutting edge extending beyond said concave edges, said blade being removable by a straight pull away from the container.

3. An envelope opener comprising a blade car- 15

rying portion, a perforating portion at one end thereof, a handle portion at the other end thereof, said handle portion being angularly offset from said blade carrying portion, a flexible housing element secured to said blade carrying portion, said housing element having a shoulder or ledge and providing a space between said housing element and said blade carrying portion, and a cutting blade insertible in the said space by direct push into the container until it rests on the said shoulder or ledge and flexibly retained therein and quickly removable therefrom, by a straight pull away from said container.

ANDREW M. LOCKETT.
